UNITED STATES PATENT OFFICE.

JOHN R. GOULD, OF RICHMOND, VIRGINIA.

ADJUSTABLE HANDLE-BAR.

SPECIFICATION forming part of Letters Patent No. 576,573, dated February 9, 1897.

Application filed January 3, 1896. Serial No. 574,258. (No model.)

To all whom it may concern:

Be it known that I, JOHN R. GOULD, a citizen of the United States, residing at Richmond, in the county of Henrico and State of Virginia, have invented a new and useful Adjustable Handle-Bar, of which the following is a specification.

This invention relates to an improvement in adjustable handle-bars for bicycles, and has for its object to provide a simple, strong, and efficient construction of coupling between the handle-bar and its stem, the said coupling being adapted to be loosened and tightened by the rider while in the saddle, so that the handle-bar may be readily adjusted to any desired angle or pitch, suitable either for hill-climbing or speeding on smooth and level roads.

The invention also has for its object to provide a coupling between the handle-bar and its stem of such construction as to admit of the handle-bar being detached from the machine.

The invention also contemplates forming the handle-bar in two substantially equal sections, which are constructed to telescope at their inner contiguous ends and adapted to be united and secured to the handle-bar stem by one and the same coupling device.

With the above objects in view the invention consists in certain novel features and details of construction and arrangement of parts as hereinafter fully described, illustrated in the drawings, and finally pointed out in the claims.

In the accompanying drawings, Figure 1 is a perspective view of a handle-bar and stem, the same being connected by means of the improved coupling. Fig. 2 is a section through the same parts, taken longitudinally of the handle-bar. Fig. 3 is a sectional view taken at right angles to Fig. 2. Fig. 4 is a perspective view showing the telescoping inner ends of the handle-bar sections. Fig. 5 is a similar view of the coupling-sleeve, in which the ends of the handle-bar sections are received and seated.

Similar numerals of reference designate corresponding parts in the several figures of the drawings.

Referring to the accompanying drawings, 1 designates the handle-bar of a bicycle, of any

desired or preferred configuration or curvature, the extremities thereof under normal conditions being deflected or curved rearwardly and provided with the usual handles or grips. For the purpose of carrying out the present invention the said handle-bar, which is preferably made of steel tubing, is divided centrally or formed in two substantially equal sections, and these sections are formed with thickened portions 2 at their meeting ends for imparting additional strength to such ends at the point of coupling and to adapt one of the sections to receive a reduced tubular extension 3 of the adjoining section, the said tubular extension having an external diameter which will adapt it to slide and fit snugly within the end of the other section, the said tubular extension being of sufficient longitudinal extent to firmly brace the two parts of the handle-bar with relation to each other.

Each of the handle-bar sections is provided adjacent to its inner end with a segmental bearing-flange 4, extending approximately one-half way around the same, and these flanges are provided about centrally with inwardly-projecting offsets or extensions 5, which meet and abut at the point 6. One of the meeting surfaces at the point 6 is provided with a radial groove 7, substantially semicylindrical in cross-section, the said groove being adapted to receive a corresponding projection or tongue 8 of substantially semicircular cross-sectional shape upon the meeting surface of the opposing offset 5, thus establishing an interlocking engagement between the ends of the handle-bar sections. This interlocking feature is usually provided by drilling radially between the meeting surfaces of the offsets 5, one-half of the bore being located in each of the meeting surfaces, a dowel pin or key being thereafter inserted into one of the semicircular half-bores and brazed or otherwise permanently secured therein. The segmental bearing-flanges 4 are made tapering from one end to the other or cam-shaped, their outer peripheral surfaces being eccentric to the axis of the handle-bar, and in addition thereto the outer opposite surfaces of said bearing-flanges are undercut or dovetailed, as shown at 9.

10 designates the handle-bar stem, which is preferably made of tubing and has at its up-

per end a cap 11 of larger diameter than the body of the stem, the said cap being provided in its upper surface with a concavity 12, whereby the said cap is adapted to fit snugly 5 against and partially embrace the lower surfaces of the segmental bearing-flanges on the handle-bar sections.

13 indicates the coupling-sleeve, which is preferably formed from a drop-forging to im- 10 part the requisite strength thereto. This coupling has a central aperture, the same being internally threaded to receive a hollow binding-screw or threaded sleeve 14, which surrounds the handle-bar stem and is pro- 15 vided at its lower end with a knurled annular flange 15, facilitating the turning of said screw or sleeve by hand. Within the central aperture of the coupling-piece 13 is formed an internal shoulder 16, which receives the head 20 or cap of the fork-stem, the said head or cap being adapted to be operated upon in the up- 25 ward adjustment of the screw or sleeve 14 for raising said head or cap and binding the same against the handle-bar sections.

25 The upper portion of the coupling-piece 13 is in the form of a hollow half-cylinder struck on the arc of a circle, corresponding closely to that of the segmental bearing-flanges 4, above described. At opposite sides or ends 30 this semicylindrical portion is formed with opposing segmental flanges 17, which are undercuted as to their inner adjacent faces or made dovetailed to correspond to and coöperate with the correspondingly-dovetailed 35 outer surfaces of the segmental bearing- flanges 4, whereby the handle-bar sections will be bound together when introduced into said coupling-piece, after which they may be held against rotation and escape by turning 40 upward the binding-screw 14.

From the foregoing description it will be seen that a very simple and efficient coupling device is obtained by means of which the handle-bar and fork-stem may be securely 45 and detachably united. By reason of the eccentric relation of the peripheral surfaces of the bearing-flanges on the handle-bar sections the farther the handle-bar is rotated in one direction the more firmly will the said 50 flanges bind against the head or cap of the stem. By loosening the binding-screw the handle-bar may be loosened and turned farther, and by loosening the binding-screw suf- 55 ficiently the handle-bar may be turned far- enough to effect a disengagement between the dovetailed flanges thereof and of the coupling-piece 13, after which the handle-bar may be entirely removed from the machine.

The purpose in making the handle-bar in 60 two separable sections is to enable the same to be carried the more conveniently in the hand or pocket when not using the machine.

When the handle-bar is removed, it will be 65 impossible for any one to mount the machine and ride off with it, thus tending to prevent the machine from being stolen by a person able to ride the same.

When it is desired to again attach the handle-bar to the machine, the sections thereof are again associated, as previously described, 70 and the flanges 4 of the handle-bar introduced between the flanges of the coupling-piece 13, after which the handle-bar is turned until the desired pitch or angle is given thereto. By now turning the binding-screw or threaded 75 sleeve 14 upward the head or cap of the stem is forced into frictional engagement with the bearing-flanges of the handle-bar, after which it will be impossible to turn the said handle- 80 bar until the binding-screw is again loosened.

By the described construction it will be seen that the angle or pitch of the handle- 85 bar may be readily adjusted by the rider while in the saddle and without the necessity of dismounting; also that the handle-bar may be set in line with the wheels, thus providing a straightway bar.

Various changes in the form, proportion, and minor details of construction may be re- 90 ported to without departing from the spirit or sacrificing any of the advantages of this invention.

Having thus described the invention, what is claimed as new is—

1. A handle-bar for cycles provided with a 95 segmental dovetailed flange, in combination with a handle-bar stem detachably connected thereto and having a coupling-piece formed to receive said dovetailed flange, and a hollow binding-screw surrounding said stem and 100 engaging the coupling-piece for causing the latter to clamp the handle-bar and prevent its rotation, substantially as described.

2. An adjustable handle-bar for bicycles, consisting of two substantially equal sections, 105 one of which is formed with an extension adapted to enter the contiguous end of the ad-joining section, said sections being provided at their meeting ends with abutting flanges, in combination with a handle-bar stem hav- 110 ing a movable undercuted socket to receive the ends of said sections and to engage said flanges, and a hollow binding-screw having a threaded connection with the socket and sur- 115 rounding the handle-bar stem to engage a fixed projection thereon and adapted when tightened to hold said sections rigidly, sub-stantially as described.

3. In an adjustable handle-bar for bicycles, the combination with the handle-bar stem, 120 and a coupling-piece thereon having a dove-tailed flange, of a handle-bar proper, pro- 125 vided with a dovetailed bearing-flange par-tially surrounding the same and engaging the flange of the coupling-piece, and a hollow binding-screw surrounding the stem and co-operating with said bearing-flange for hold-ing the handle-bar against rotation, substan-tially as set forth.

4. An adjustable handle-bar for bicycles, 130 comprising a handle-bar proper made in two substantially equal sections having interlocking engagement at their contiguous ends and formed with opposing dovetailed flanges par-

tially surrounding the same, a handle-bar stem having an expanded cap or head portion, a coupling-piece loosely mounted upon the stem and engaging beneath said head or cap and also provided with a substantially semicylindrical upper portion forming a seat for the handle-bar, opposing dovetailed flanges at the opposite sides or ends of said semicylindrical portions, adapted to coöperate with the corresponding flanges of the handle-bar, and a hollow binding-screw sur-

rounding the stem and entering the coupling-piece, the said screw being adapted to bind the handle-bar within the coupling-piece, substantially as and for the purpose described. 15

In testimony that I claim the foregoing as my own I have hereto affixed my signature in the presence of two witnesses.
